UNITED STATES PATENT OFFICE.

CHARLES S. HOOPER, OF ERIE, PENNSYLVANIA.

WATER-TUBE BOILER.

No. 920,139.

Specification of Letters Patent.

Patented May 4, 1909.

Application filed July 17, 1908. Serial No. 444,108.

To all whom it may concern:

Be it known that I, CHARLES S. HOOPER, a citizen of the United States, residing at Erie, in the county of Erie and State of Pennsylvania, have invented certain new and useful Improvements in Water-Tube Boilers; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to water-tube boilers and has for its objects the improvements in the construction of the headers, and in the connection of the headers with the steam-drum by means of a corrugated tube, whereby the excess expansion of the tubes over that of the steam-drum is provided for and the injurious effects thereof, so usual in water-tube boilers of this type, are entirely overcome.

The features of my invention are herein-after fully set forth and described, and illustrated in the accompanying drawings in which:

Figure 1 is a side elevation of a water-tube boiler with parts broken away, embodying my improvements. Fig. 2 is an end view in elevation of a half section of the same. Fig. 3 is a top or plan view of one of my improved boiler-headers. Fig. 4 is a side view in elevation of a portion of one of the two half header-sections. Fig. 5 shows a plate cut into shape to be formed up into a one half section of my improved boiler-header.

In the drawings A is the steam-drum and B the water-tubes of an ordinary water-tube boiler.

In the construction of the headers C and C' of my improved boiler, I take a plate D of metal and cut it into the shape substantially as shown in Fig. 5. It is then formed up substantially into the shape shown in Fig. 4, by turning the edges D thereof inward substantially on the broken lines d and d', so as to form a one half section of the header having an inturned peripheral flange or edge D' and an oval half collar D² thereon at the upper edge thereof, and when two sections thereof are placed together, one preferably

slipped within the other, and the two riveted together, they form a complete header f 55 with an oval collar D² on the upper edge thereof ready to receive the connection to the steam-drum A.

In the drawings I have shown my improved connection E only between the rear header and the steam-drum. This connection E I make of a section of corrugated tube of suitable length, which corrugated tube I preferably flatten into an oval shape and insert one end of the same into the collar D³ 65 and rivet the same therein in the usual manner, and to the under side of the steam-drum A, I rivet an oval flanged collar F which will receive the upper end of the connection E, which is then riveted therein. 70

I have shown the connection G between the front header C and the steam-drum A as having a flanged collar F' secured to the steam-drum A made long enough to pass over the outside of the collar D³ on the top of 75 the header C and be riveted thereto. I can however use a section of corrugated tube for making this connection if I so desire. By the use of this corrugated tubing for the connection E, I avail myself of the superior 80 flexibility of the corrugations therein, and thereby form a comparatively flexible connection between the header C' and the rear of the steam drum A, which operates as a yielding or flexible connection between the 85 header and the steam-drum, and overcomes the excess expansion of the tubes B over the expansion of the steam-drum A, and thereby prevents the injurious effects thereof.

Having thus described my invention so as 90 to enable others to utilize the same, what I claim as new and desire to secure by Letters-Patent of the United States is:

1. A half section of a boiler-header having an inturned peripheral flange, and a half 95 collar projecting from its upper edge formed up from an integral plate of metal, substantially as set forth.

2. A boiler-header consisting of two substantially duplicate half sections riveted 100 together, each of said sections having integral inturned edges and half-collars thereon, substantially as set forth.

3. The combination of a boiler-tube-header having a series of water-tubes 105 secured therein, a steam-drum, and a corrugated

gated tube connecting said header and steam-drum, substantially as set forth.

4. The combination of a steam-drum, a flanged collar thereon, a header comprised of substantially duplicate half sections riveted together, a collar formed on said header integral therewith, and a corrugated tube riveted at one end to the collar on the steam-

drum, and at the other to the collar on the header, substantially as set forth.

In testimony whereof I affix my signature, in presence of two witnesses.

CHARLES S. HOOPER.
